UNITED STATES PATENT OFFICE

HARRY WAGNER, OF ST. LOUIS, MISSOURI

RADIATOR OVERFLOW

Application filed May 8, 1928. Serial No. 276,119.

The cooling liquid in the radiator of an internal combustion engine expands when heated and wastes either by overflowing or passing off as vapor. This is objectionable when 5 an anti-freeze mixture is employed in cold weather because of the expense incident to replacement.

The present invention provides simple and inexpensive means for preventing waste and 10 obviating frequent replacement of the radiator liquid, since the vapor and overflow are trapped and automatically returned to the radiator as the latter cools.

The invention contemplates a tank, or receptacle, of any shape and size conveniently disposed to be out of the way and hidden from view, connected with the top of the radiator and disposed at such an elevation that the overflow and condensate automatically 20 return to the radiator.

While the drawing illustrates a preferred embodiment of the invention, it is to be understood that in adapting the means to meet specific needs and requirements the design 25 may be varied and such other changes in the minor details of construction may be resorted to within the scope of the invention as claimed, without departing from the spirit thereof.

For a full understanding of the invention and the merits thereof, reference is to be had 30 to the following description and the drawing hereto attached, in which,—

Figure 1 is a side view illustrative of an 35 embodiment of the invention.

Figure 2 is an enlarged sectional view of 40 a tank or receptacle for the overflow and vapor from the radiator of an internal combustion engine.

Corresponding and like parts are referred 45 to in the following description and designated in the several views of the drawing by like reference characters.

In the drawing, wherein for the purpose of 50 illustration is shown a preferred embodiment of the invention, the numeral 1 denotes an internal combustion engine and 2 the radiator included in the cooling system, such parts being of well known construction and arrangement.

The numeral 3 denotes a tank or receptacle adapted to receive the overflow and vapor from the radiator when heated. This tank may be of any capacity and design and is conveniently located to be out of the way and not 55 interfere with the appearance of an automobile or other vehicle. The tank is usually located beneath the cowl or hood and at an elevation to admit of the overflow and condensate returning to the radiator. A pipe 4 connects the bottom of the tank 3 with the top of the radiator 2 so that overflow and vapor from the radiator will readily enter the tank and accumulate therein, the vapor condensing 60 in the pipe and tank. An overflow pipe 5 connects with the bottom of the tank 3 and extends to the top thereof and slants at its upper end, as indicated most clearly in Figure 2 of the drawings to insure the maintenance of an outlet for any possible overflow in the 65 event of the tank filling to a critical extent.

The pipe 4 is preferably flush with the bottom of the tank to drain the latter and admit of all the contents returning to the radiator 2. 70

When the radiator becomes heated vapor passes off therefrom through the pipe 4 into the tank 3 and condenses and accumulates in the tank. Should the radiator heat to such an extent as to cause the liquid to flow therefrom it is directed by the pipe 4 into the tank 3. 75 Should the accumulation be such as to fill the tank 3 or the pressure therein become critical a release is provided by means of the overflow pipe 5 through which the excess of pressure 80 or liquid escapes. When the radiator cools the contents of the tank 3 return by way of the pipe 4 to the radiator and in consequence, waste of antifreeze mixture is prevented and 85 frequent refilling of the radiator overcome.

Having thus described the invention, I 90 claim:

The combination with the radiator included in the cooling system of an internal combustion engine, of a concealed tank remotely 95 situated from the radiator and at an elevation wholly above the normal level of the water therein, a pipe leading from the bottom of the tank and connecting with the top of the radiator and in communication therewith at a 100

point coinciding with the normal water level therein, and an overflow pipe connected with the bottom of the tank and extending upwardly therein and terminating adjacent the top thereof and having its upper end slanted.
5 In testimony whereof I affix my signature.

HARRY WAGNER. [L. S.]
